UNITED STATES PATENT OFFICE.

THOMAS FAIRLEY, OF LEEDS, ENGLAND.

APPARATUS FOR CONDENSING AND COOLING VAPORS OR LIQUIDS.

SPECIFICATION forming part of Letters Patent No. 627,774, dated June 27, 1899.

Application filed December 23, 1897. Serial No. 663,175. (No model.)

To all whom it may concern:

Be it known that I, THOMAS FAIRLEY, a subject of the Queen of Great Britain and Ireland, and a resident of Leeds, in the county of York, 5 England, have invented a certain new and useful Improved Apparatus for Condensing and Cooling Vapors or Liquids, (for which I have obtained a patent in Great Britain, No. 4,536, bearing date February 19, 1897,) of which the 10 following is a specification.

The object of my invention is to construct simple and efficient apparatus whereby vapors, gases, or liquids may be quickly cooled without waste of the cooling agent, and ap-

15 paratus constructed as hereinafter described are smaller and more compact in form in proportion to the work done than those generally used for the purpose and may therefore be not only constructed of copper, tin, or other 20 suitable cheap materials, but also of aluminum, silver, or platinum, without prohibitive cost.

In the drawings, Figure 1 is a vertical section, and Fig. 2 a sectional plan taken on the 25 line X X of Fig. 1, of an apparatus illustrating my invention in its simplest form; and Fig. 3 is a vertical section, and Fig. 4 a sectional plan taken on the line Y Y of Fig. 3, 30 illustrating the same apparatus adapted for treating larger quantities of vapor or liquid required to be cooled.

Referring to Figs. 1 and 2, I construct a double cone, which is composed of two thin cones A and B, joined together base to base, and 35 the apexes of the cones A and B are provided with inlet and outlet tubes C and D for the supply and discharge of the cooling agent. A jacketed chamber is formed on the exterior of the double cone A B by means of two cones 40 E and F, which are connected together base to base, and a tube G is provided for the entrance of the vapor to be condensed, while a tube H carries off the condensed liquid. The ends of the tubes C and D are turned within 45 the cones A and B, so as to supply and withdraw the cooling agent directly to and from their apexes, thus preventing the cooling agent remaining stagnant adjacent to the end of the cones.

50 The cooling agent as it enters the inner double cone by the tube C is projected into the

apex of the cone B by the turned-down end of the said tube C. The cooling agent then rises, collecting heat as it ascends, until it reaches the apex of the cone A, where it is drawn off 55 by the tube D. As the fluid enters at the tube G it impinges on the exterior of the apex of the cone A, and this has the effect of spreading the stream of fluid and diverting it down the sides of the cone A. Condensation is effected by the cooling agent within the cone A, and the fluid meets an increased condensing or cooling surface till it comes to the line of junction of the cones, and the fluid is led by the cone F to the tube H. 60

65 By inclosing the apparatus above described with a third double cone J K, as seen at Figs. 3 and 4, an outer jacket is provided for the circulation of a cooling agent, and I thus obtain a more powerful apparatus suitable for 70 use on a larger scale. In this case the side tubes C and D pass through the cones E and J and F and K and connect to the cones A and B near their apexes, and the outer jacket inclosed within the double cone J K is provided with inlet and outlet tubes M and N for 75 the supply and discharge of the cooling agent, which tubes M and N connect to the cones J and K near their narrowest parts, the tube N being seen in Fig. 4 with the extremity of 80 the tube M projecting behind same.

The action of the outer jacket formed by the cones J and K is similar to that of the double cone A B, and the cooling agent is taken off at the top in both cases, and this cumulative management of the cooling agent, combined with the dividing action of the apex of the cone A, enables the apparatus described to condense vapor or cool liquids with minimum expenditure of cooling agent. 90

I do not claim a cooling or condensing device having conical ends.

I claim as my invention—

1. The cones A, B, united at their bases and forming a vessel for cooling liquid with the 95 supply-pipe C, opening into the bottom end of the cone B, and turned down to direct the liquid to the apex of the cone, and the discharge-pipe D, opening up into the apex at the top end of the cone A, in combination with 100 the surrounding vessel composed of the inverted cones E, F, with the inlet-pipe G, at

the upper end for the fluid to be cooled, and the discharge-pipe H, at the lower end, substantially as specified.

2. The cones A, B, united at their bases 5 and forming a vessel for cooling liquid, with the supply-pipe C, opening into the bottom end of the cone B, and turned down to direct the liquid to the apex of the cone, and the discharge-pipe D, opening up into the apex 10 at the top end of the cone A, in combination with the surrounding vessel composed of the inverted cones E, F, with the inlet-pipe G, at

the upper end for the fluid to be cooled and the discharge-pipe H, at the lower end, and the exterior jacket composed of the united 15 cones J, K, and inlet-pipe M, near the bottom of the cone K, and the discharge-pipe N, near the top of the cone J, substantially as specified.

THOMAS FAIRLEY.
